UNITED STATES PATENT OFFICE.

EDWARD H. WEATHERHEAD, OF CLEVELAND HEIGHTS, OHIO, ASSIGNOR TO THE BISHOP & BABCOCK COMPANY, OF CLEVELAND, OHIO, A CORPORATION OF OHIO.

ELECTRICAL SWITCH.

Application filed March 3, 1923. Serial No. 322,464.

The present invention relates to switch mechanism, the principal object of the invention being the provision of a simple and quick acting snap switch. To the accomplishment of the foregoing and related ends, 5 said invention, then, consists of the means hereinafter fully described and particularly pointed out in the claim.

The annexed drawing and the following 10 description set forth in detail certain mechanism embodying the invention, such disclosed means constituting, however, but one of various mechanical forms in which the principle of the invention may be used.

15 In said annexed drawing:—

Fig. 1 is a vertical section through one 20 form of my improved switch mechanism showing the parts thereof in elevation; Fig. 2 is a similar view, but showing a modified form of mechanism; and Fig. 3 is a section on the line 3—3, in Fig. 1.

In Fig. 1 there is shown a casing 1, in 25 which is mounted the switch mechanism proper, the switch mechanism being designed to electrically connect spaced contact members 2 and 3 which are electrically insulated from the casing 1 and passed through the same where they are engaged by removable nuts 4 and 5, respectively, for attaching the wires to an electric circuit.

A switch member 6 is provided, consisting 30 of a plurality of resilient strips of metal 6, 7, 8 and 9, having their ends in approximate alignment adapting them for engagement with the flat contact members 2 and 3 upon movement of the switch member into the position shown in Fig. 2, for example. The switch member 6 is carried on the end of a block 10 of insulating material by means 35 of a screw 11 and spring 12, the spring 12 serving to hold the various strips 6, 7, 8 and 9 in close contact between the flanges 13 formed on the end of the block. The links 40 14 and 15 are preferably in the form of a square tube as shown or are U-shaped although of course each link may be a single strip or two unconnected strips. The block 10 is pivotally mounted by means of links 45 14 and 15 to which is pivotally attached the block 10 at the points 16 and 17, respectively, while the links are in turn pivotally mounted at the points 18 and 19, respectively, to the casing. This block 10 is movable from left to right and return, toward 50 and away from the contacts 2 and 3, and

its movement is in the arc of a circle, but this circular movement of the switch member in no way affects the action of the switch because of the construction of the strips 6, 7, 8 and 9.

The member 10 is moved into the circuit closing position by means of a lever 20 pivoted about an axis 21, and provided with two spaced arms 23 and 24, which engage against a pin 25 formed on the block 10. 60 The lever 20 is provided with an opening 26 engaging over a pin 27 on the block 10, which provides a second loose engagement between the lever and the block. A spring 28, connected to the outer end of the lever 70 20 and to a bracket 29 at the bottom of the casing, serves to hold the upper portion of the lever 20 in engagement with the pin 27, as indicated in Fig. 1. A telescoping spring member, consisting of an outer casing 30, an 75 inner block 31 and an intermediate spring 32, is mounted between a socket 33 in the upper part of the casing, and a second socket 34, formed in the top of the block, the action of the spring 32 being to maintain the block 80 10 either in the position shown in Fig. 1 or in the position of Fig. 2, this spring being compressed as the telescope is brought past its central or vertical position. The telescoping spring member is adapted to hold 85 the block 10 in either the open or closed position of the switch and to prevent accidental movement of the block which might move when the member 20 is in an intermediate position and exerting no holding action on the pin 25. When in such intermediate position the telescope member exerts sufficient 90 pressure to prevent the block from movement and the spring 28 is strong enough to move the block against the pressure of the 95 spring 32 until it has passed its vertical position.

The operation of the switch is effected by means of a bell crank lever 35 pivoted about an axis 36 and having a yoke 37 formed at 100 one end and engaging over the lower end 38 of the lever 20. Pivotal movement of this bell crank lever 35 at first swings the lever 20 until one of the lugs 23 or 24 thereon engages the pin 25 on the block 10, and moves this 105 block past the central position of the springs 32 and 28. As soon as these springs have been brought past their control position they act to snap the block 10 through the remainder of its movement, and either into 110

or out of engagement with the contacts 2 and 3, depending upon the direction of movement of the lever 35. As is shown in Fig. 1, the outward or disconnecting movement of the block is limited by contact with the adjacent wall of the casing.

The construction shown in Fig. 2 is similar to that of Fig. 1, except that the operating means there consists of a bell crank lever 10 40 pivoted about an axis 41 and normally held in the position there shown by means of a spring 42 operating between a holder 43 and a socket 44 formed in one end of the lever 40. This lever 40 is operated by means 15 of a disk 46, having a projection 47 engaging in the socket in the lower arm 48 of the bell crank lever. The disk 46 is in turn mounted against a diaphragm 49, which is operated upon a certain increase in pressure 20 in the chamber 50 on the outer side of the diaphragm, the pressure fluid entering this chamber through an opening 51 therein.

The present switch mechanism is extremely simple and inexpensive in construction, 25 and provides a snap action which is desired to prevent arcing when the switch is opened or closed.

Other modes of applying the principle of my invention may be employed instead of 30 the one explained, change being made as re-

gards the mechanism herein disclosed, provided the means stated by the following claim or the equivalent of such stated means be employed.

I therefore particularly point out and distinctly claim as my invention:—

In a switch mechanism, the combination of a base, spaced contacts mounted on said base, a resilient switch member adapted in one position to engage and electrically connect said contacts, an insulating block carrying said switch member at one end, a fixed abutment adjacent to the other end of said block, parallel links each pivoted at one end to said base and at their opposite ends to said insulating block, resilient means acting against said block on the side opposite the base pivots of said links, said means being adapted to move said block to one of two limiting positions toward said contacts and toward said abutment when said block has first been moved to a predetermined position, and means movable relatively to said block and having a dual lost motion connection therewith for moving the same to a position wherein said resilient means will be brought into action.

Signed by me this 2nd day of February, 1923.

EDWARD H. WEATHERHEAD.
